CLAIM

The ornamental design for a hood of a construction machine, as shown and described.

DESCRIPTION

FIG. 1 is a rear perspective view of a hood of a construction machine, such as a motor grader, in accordance with a first embodiment of the present design.

FIG. 2 is a rear view of the hood of FIG. 1.

FIG. 3 is a front view of the hood of FIG. 1.

FIG. 4 is a right side view of the hood of FIG. 1.

FIG. 5 is a left side view of the hood of FIG. 1.

FIG. 6 is a top view of the hood of FIG. 1; and,

FIG. 7 is a bottom view of the hood of FIG. 1.
